UNITED STATES PATENT OFFICE.

IRA D. VINTON, OF LOS ANGELES, CALIFORNIA, ASSIGNOR TO ROBERT B. COLEMAN, OF LOS ANGELES, CALIFORNIA.

MATERIAL-COMPRESSING MACHINE.

1,260,605.

Specification of Letters Patent. Patented Mar. 26, 1918.

Application filed May 13, 1915. Serial No. 27,741.

To all whom it may concern:

Be it known that I, IRA D. VINTON, a citizen of the United States, residing at Los Angeles, in the county of Los Angeles and State of California, have invented certain new and useful Improvements in Material-Compressing Machines, of which the following is a specification.

This invention relates to improvements in material compressing machines, and particularly to such as are adapted for compressing comminuted material, as saw dust, shavings, chips, straw, hay, feed, pulp and the like to form briquets, sticks or blocks of the same, for fuel or other purposes.

It is an object of the present invention to provide a machine of this kind in which the mechanism for binding the compressed materials is greatly simplified over former machines of the same general type.

It is also an object of the invention to provide a cam mechanism for separating the compressed materials into masses or sticks of a suitable length, the separating mechanism being adapted to lock the parts in their normal positions when they are receiving the compressed materials.

The invention comprises certain novel constructions, combinations and arrangements of parts as will be hereinafter fully described and claimed.

In the accompanying drawing forming part of this specification:

Figure 1 is a front elevation of a machine constructed in accordance with the present invention.

Fig. 2 is a vertical central sectional view taken through the machine to one side of the plunger mechanism, parts of the die, rotating device and separating mechanism being shown in elevation.

Fig. 3 is a detail longitudinal sectional view taken through the forming die and the material rotating mechanism, the parts being shown upon an enlarged scale.

Fig. 4 is a top plan view of the sectional dies for forming the material compressed into sticks, the platform supporting platform therefor being broken away.

Fig. 5 is a horizontal transverse sectional view taken upon the line 5—5 of Fig. 3.

Fig. 6 is a front edge view of the cam mechanism for controlling the material sep-

arating and rotating means and the wire cutting device, together with the means for tripping the same.

Fig. 7 is a side elevation of the same, adjacent parts of the machine being shown.

Fig. 8 is a detail view of a portion of the trip rod of the mechanism, showing the pivoted cam block carried thereby.

Fig. 9 is a horizontal transverse sectional view taken upon the line 9—9 of Fig. 2.

Fig. 10 is a horizontal detail sectional view taken upon the line 10—10 of Fig. 3.

Fig. 11 is a horizontal detail sectional view taken upon the line 11—11 of Fig. 7.

Fig. 12 is a fragmentary detail view showing the wire cutting mechanism.

Fig. 13 is a detail fragmentary view showing adjacent ends of the forming die and of the material separating and rotating member separated for twisting and cutting the wires.

Fig. 14 is a detail perspective view of a completed stick of compressed material with the binding wires applied thereto.

Fig. 15 is an enlarged fragmentary detail view showing one of the studs in section for operating one of the wire cutting blades.

Fig. 16 is a detail sectional view through the lower part of the material rotating mechanism and illustrating a modified form of the clutch mechanism.

Fig. 17 is a view partially in section and partially in elevation of the lower portion of the machine showing a modified form of the clutch driving mechanism.

Fig. 18 is a detail perspective view of one of the double slotted brackets for adjustably holding the bar or plate which carries the wire cutter.

The present invention is designed to afford a simple and effective means by which saw dust, shavings or other waste products in more or less comminuted form may be compressed into masses or sticks of suitable size and length for use in various ways, and particularly for use as a fuel. I am aware

that machines of this type have been heretofore used and it is the purpose of the present invention to simplify the mechanism and especially that employed for separating the compressed materials into masses, sticks or compressed bodies of a proper size or length, and also the mechanism employed for rotat-

ing the separated masses to twist the binding wires thereon, as well as the mechanism for cutting the wires.

In the accompanying drawings the preferred forms of the mechanisms embodying the features of the invention, have been illustrated, and the details and features of said invention will now be more specifically described and claimed, reference being had to said drawings in which 15 indicates the frame of the machine, 16 a compressing plunger, 17 a pitman for operating the same and 18 a shaft carrying a crank disk 19 with a wrist pin 20 thereon for actuating said pitman. The shaft 18 is mounted in suitable bearings at the top of the frame 15 and has secured thereon a gear wheel 21 which meshes with an actuating pinion 22 mounted upon a power shaft 23. A pulley 24 loosely carried by said shaft 23 is adapted to be connected by a belt 25 with any suitable source of power not shown, and a clutch mechanism 26 of any suitable type and operable by means of a handle 27 is generally employed for connecting the power driven pulley 24 with the shaft 23.

The plunger 16 is carried by reciprocating head 28, pivotally connected with the pitman 17, and the said head moves up and down in suitable guides 29 upon the frame of the machine. The said head 28 also carries a laterally projecting arm 30 which is adapted to operate the cam mechanisms of the machine as will be hereinafter more fully described.

Below the plunger 16 the frame 15 is provided with a horizontal platform 31 having an opening therein to receive the members of the forming die of the machine. The said opening as 32 is provided with an offset annular recess 33 at the top to receive the supporting flanges 34 and 35 of die sections 36 and 37. The die sections are substantially semi-cylindrical and the section 36 is rigidly secured in place by bolts 38. The lower end of the said die section which extends considerably below the platform 31 is also braced by a proper abutment, as for instance a rod 39 having adjustable bolts on the end thereof as shown in Figs. 1 and 3. The other die section 37 is mounted in the opening 32, which recedes from the die section in the lower portion thereof, so as to rock slightly upon the upper edge of said opening. The flange 35 of said section is also tapered as clearly shown in Fig. 3 so as to permit of the slight rocking movement desired in the die section. The said movable die section 37 when thus recessed in the platform 31 is held with respect to the fixed die section 36, as if the parts were hinged together at the top. The lower end of said rocking die section 37 is normally held in proper relation to the other die section by an abutment screw 40 which engages a screw threaded opening

41 in the adjacent standard of the frame 15. A lever handle 42 applied to the outer end of the said abutment screw makes it possible to slightly release or ease up upon the lower end of the die section 37, in the event of the materials becoming too tightly wedged within the die. A slight turn of the screw for a moment is usually sufficient to relieve any clogging of the die, after which the die section can be returned to its normal position. 75

The die sections 36 and 37 are also preferably provided with lining sections 43 substantially semi-cylindrical and held against turning within the die sections by screws 44.

The meeting edges of the said die sections 80 and the said lining sections are cut away at 45 to accommodate a trip wheel 46 having a serrated edge extending into the die a sufficient distance to engage the stick of compressed material, whereby the trip wheel is 85 operated for moving a trip rod, as will be hereinafter more fully described and claimed.

In compressing waste materials such as saw dust, shavings and the like to form a composite fuel, it is necessary to bind the 90 masses or sticks of compressed material with suitable holding means, as for instance binding wires, and it is found in practice that the said binding means or wires must be well embedded in the sticks compressed, in order 95 to prevent the materials from curling out from under the wires when the sticks are burning, whereby the said sticks become disintegrated too rapidly to make a good fuel. The lining sections 43 are therefore made 100 with kerf forming knives or blades 47 usually arranged opposite each other as shown in Figs. 3 and 4 and extending from a point just below the reach of the compressing plunger 16 to points near the lower end 105 of the die, where openings 48 are provided for the introduction of binding wires 49. As the materials are compressed by the plunger 16 and forced downwardly through the die, the knives 47 form and maintain kerfs 110 or longitudinal grooves in the compressed stick to receive the wires 49. Below the openings 48 pieces 50 are also carried by the die sections 43 of nearly the same width as the knives 47 but not having sharp edges, by 115 which the wires are forced into the kerfs to the full depth thereof. The ends of the wires are twisted together so as to fasten them around the end of the stick. The wires are drawn from spools as 51 mounted in any 120 suitable position upon the frame of the machine.

As the compressed stick of material becomes more and more elongated it passes out of the lower end of the die and is received 125 by a rotating mechanism made up of an elongated cylindrical member 52 which engages a bearing 54 in a shelf or platform 55 mounted between a central and side standard of the frame 15. The lower end of the cyl- 130

inder is reduced in diameter as at 56 and has a bearing in a sleeve member 57 of a clutch device. The said sleeve member 57 engages a bearing 58 upon the base of the machine. 5 The platform or shelf 55 has a depending annular flange forming an extension of the bearing 54, and the said flange is slotted at 59 in its opposite walls to receive and guide trunnions 60 which project from a bearing 10 ring 61. The upper portion of the cylinder 52 is formed by a removable cylinder section 62, between which and the end of the lower portion of the said cylinder 52 is an annular space to receive the bearing ring 61, as will 15 be readily understood by reference to Fig. 1 of the drawing. The cylinder 52 is thus revolvably supported by the said bearing ring 61. Recessed within the said cylinder 52 are semi-cylindrical lining sections 63, having 20 an annular flange 64 at the top which overhangs and rests upon the upper end of the cylinder structure. Near the upper end of the said cylinder structure a pair of C-springs 65 are mounted in an annular recess 25 66 so that their free ends bear upon the lining sections and hold them together with a yielding pressure as will be understood by reference to Fig. 10 of the drawing. The said sections 63 thus receive and hold the 30 compressed stick of materials, with a firm enough hold to rotate the same when the cylinder 52 is rotated, for twisting the binding wires 49, but will yield sufficiently to prevent any sticking or clogging of the material within the parts. 35

When a stick of compressed material, of a desired length has been forced from the die into the sections 63, and the cylinder 52 carrying the same, the cylinder 52 is 40 lowered for breaking the stick at the lower end of the die, and separating the parts sufficiently to permit of the twisting of the binding wires between them. The said cylinder 52 is lowered at the proper time by a 45 lever 67 which is fulcrumed upon a fulcrum rod 68 which extends between adjacent standards of the machine beneath the platform 55 which support the said rod, the inner end of the lever 67 being preferably bifurcated so as to straddle the bearing flange 50 in which the cylinder 52 moves, the ends of said bifurcated portion having bearings receiving the outer ends of the trunnions 60. The movement of the lever 67 upon its fulcrum bar 68 is thus capable of moving the trunnions 60 up and down in the slots 59 and correspondingly raising and lowering the cylinder 52. The outer end of the said lever 55 67 is provided with a cam arm and locking member 69, the operation of which will be hereinafter fully set forth.

The engagement of the reduced end 56 of the cylinder 52 with the clutch member 57 is such that it may be rotated by the operation 59 of the clutch of which the member

57 is a part. The reduced cylinder portion 56 has a splined connection with the member 57 at 70 so that the said reduced portion may move longitudinally within the member 57, but must turn with it when it is rotated. 70 The upper end of the member 57 is provided with an outwardly extending annular flange forming a circular plate 71 to which an operating lever 72 for a clutch band is pivotally secured, at 73. Revolvably mounted 75 upon the clutch member 57 is a clutch drum 74 which is carried by a beveled gear 75. The said bevel gear 75 rests against a bearing collar 76 rigidly secured to the member 57, the said collar also holding the member 80 with respect to the bearing 58 in the base of the machine. A similar bearing collar 77 is also rigidly fastened to the member 57 below said bearing 58 to prevent any longitudinal movement of the member 57 in said bearing. The drum 74 is constantly rotated by the gear 75 and its motion is imparted to the plate 71 and the member 57 for rotating the cylinder 52, by the tightening of a clutch band 78, which surrounds the said drum 74, 85 90 and has one end rigidly connected and carried by the circular plate 71 through the agency of a pin 79, which depends from the edge of said plate and engages a loop or eye 80 formed at one end of the clutch band. 95 The other end of the clutch band is fastened at 81 to the lever 72.

In order to operate the lever 72 at the proper time, a cam ring 82 is rigidly fastened on the reduced portion 56 of the 100 cylinder 52, the lower edge of said ring being beveled so that when the cylinder is lowered the end of the lever 72 which engages said cam ring will be forced outwardly and tighten the clutch band upon the drum 74. 105 The parts are so related that when the broken sections of the compressed stick have been sufficiently separated, the clutch band will be tightened sufficiently to cause the rotation of the cylinder 52 and the twisting 110 of the wires between the separated ends of the sticks. As soon as the cylinder 52 is raised again, the clutch band will be loosened and the rotation of the said cylinder will cease. 115

In order to properly drive the gear 75, a horizontal shaft 83 is mounted in suitable journal bearings near the bottom of the frame 15 and a bevel gear 84 is secured thereto and arranged to mesh with the gear 120 75 for actuating the same. A bevel gear 85 is also secured upon the shaft 83 for turning it, said gear meshing with a bevel gear 86 carried by the lower end of an inclined shaft 87. The upper end of the shaft 87 is supported by a bracket at a suitable distance from the drive shaft 23 and a bevel gear 88 secured to the said upper end meshes with a bevel gear 89 which is secured to said shaft 23. Thus when the machine is running, the 125 130

shafting and gears just described will constantly drive the gear 75 and the drum 74. In order to operate the material separating and wire twisting mechanism, and also 5 the wire clipping device, a reciprocating bar 90 is vertically mounted in the machine in suitable proximity to the arm 30 of the plunger head 28. The bar 90 is provided with a block 91 which projects beneath the 10 arm 30 and the said arm when engaging said block 91 carries the bar 90 to the lowest extreme of its movement. The arm 30 is generally carried up and down a number of times before the bar 90 is raised again, this 15 being controlled by a trip mechanism which is dependent on the length of the compressed stick that is to be formed. When the rod 90 is to be raised, a pivoted trip block 92 is thrown outwardly by means of a spring 20 93 into the path of the said arm 30, so that the next time it rises it will carry the rod with it. The said trip block 92 is normally held out of the path of the arm 30 by an S-shaped latch piece 94 which is pivoted upon 25 one side of the bar 90 and has its upper end turned outwardly so as to engage an aperture 95 formed in an arm 96 which projects from the trip block 92. The lower end of the latch piece 94 is turned inwardly and 30 normally pressed inwardly by a spring 97. The said lower end projects into the path of a cam block 98, which is pivoted at 99 on a trip rod 100. The said cam block being normally held in vertical position against a 35 limiting pin 101 by a spring 102. When the trip rod 100 is drawn downwardly, a cam face 103 on the block 98 engages the lower end of the latch piece 94 and moves it to release the trip block 92, whereby the bar 90 40 will be elevated. When the said bar is depressed again, the lower end of the latch piece 94 will engage a bevel surface 104 on the end of the said block 98 so as to force it to one side sufficiently to pass it, without 45 effect upon the said latch piece or the trip block 92. The trip rod 100 is normally pulled upwardly by a spring 105 which connects the rod with a guide bracket 106 which guides the upper end of the said trip rod, 50 as well also as the upper end of the rod 90. The lower end of the trip rod 100 is connected with an actuating lever 107, pivoted to the frame at 108 and having a curved end portion 109 projecting into the 55 path of one or more studs 110 which project from one side of the serrated wheel 46. As the composite stick descends in the die and turns the said serrated wheel 46, the pins 110 engaging the lever 107 will pull the rod 100 downwardly at proper intervals for producing the reciprocation of the rod 90. The trip block 92 is returned to its latched position when the rod 90 reaches its uppermost 60 position by passing the end of a spring

pressed bolt 111 on the bracket 106, which 65 folds the said block 92 flush with the side of the bar 90 so that the latch piece 94 again engages the aperture 95, for holding said trip block against the action of the spring 93. In order to prevent the rod 90 from 70 reciprocating except when positively moved by the arm 30, the lower portion of said bar passes between friction pieces 112 and 113 which are secured in a yoke piece 114. The free ends of said yoke piece may be drawn 75 together by a bolt 115 so as to exert just enough pressure upon the bar 90 through the friction pieces to prevent its movement, except when actuated by said arm 30.

The movement of the lever 67 by the rod 80 90 is important, it being accomplished by a stud or anti-friction roller 116 which projects from one side of the bar 90. The arm 69 is extended at an angle with respect to the lever 67 and is provided with a bent end 85 portion extending almost in a plane parallel with the lever 67, but at such an angle as to permit the formation of a cam surface 117 within a bent slot formed in said arm 69. The position of the cam surface 117 is such 90 that when the roller 116 is raised with the bar 90, the outer end of the lever 69 will be quickly raised and the cylinder 52 as quickly depressed for breaking and separating portions of the compressed stick of materials. 95 The lower end of the slot in the arm 69 is provided with an offset portion 118 adapted to be engaged by the roller 116, the relation of the said offset or notch 118, to the fulcrum rod 68 being such that the cylinder cannot 100 be depressed by pressure placed upon the bifurcated ends of said lever, the throw of the arm 69 outwardly being prevented, until the roller 116 is moved out of said offset portion by the lifting of the rod 90. The locking means thus provided for the lever 69 105 also prevents any tendency to lift the rod 90 by throwing the outer end of the lever 69 upwardly, as when the compressed stick of materials is forced into the cylinder 52. 110 The upper end of the slot in the arm 69, above the bend therein, permits of a continued upward movement of the roller 116 without raising the lever 69 after the material of the compressed stick has been 115 broken and lowered sufficiently to secure a proper length of wire between the twisted parts.

When the lower end of the compressed stick has been broken off at a suitable length 120 and the wires have been twisted as illustrated for instance in Fig. 13, the wires are cut at a point intermediate the length of their twisted portions by any suitable or desired means. Various kinds of cutters may 125 be employed within the spirit of the invention. As illustrated in the drawing, cutting blades 119 may be pivoted together and upon

- a plate 120 which is guided by suitable means upon a transverse supporting bar 121. The ends of said bar are adjustably bolted to angle brackets 122, one of which is illustrated in detail in Fig. 18. The brackets are provided with slots 123 and 124, whereby the bar 121 may be adjusted vertically and horizontally for securing a movement of the cutters 119 in a proper plane.
- 5 The outer end of the plate or slide 120 is secured to a rod 125 having a bearing in a bracket 126 which projects from the main frame of the machine. The rod 125 is reciprocated for causing the cutters to snip the wires by an anti-friction roller 127 which engages a cam plate 128, carried by the bar 90. In order to make the cutters 119 come together they are provided with bent stems or arms 129 which pass through 15 openings 130 in studs 131 which are secured with any suitable swivel mounting to the guide pieces for the plate 120 upon the under side of the transverse supporting bar 121. The rounded walls of the openings 130 as 20 clearly shown in Fig. 15 facilitate an easy sliding of the stems 129 therein, as the cutters are moved back and forth.
- The anti-friction roller 127 engages a curved cam path 132 as the rod 90 rises, the 25 lower portion of said path thrusting the cutters against the wires. The roller also passes a spring actuated switch piece 133 pivoted in the lower portion of the cam path and when the cam plate rises to the full height that it is carried by the bar 90, the said switch piece will close the lower end 30 of the cam path 132 behind the roller 127, so that as the bar 90 descends again, the said roller will be moved farther by the switch 133 to complete the wire cutting, and be caused to pass through an inclined return path 134, whereby the roller is prevented from catching in any way upon the inner wall of the path 132 upon the return 35 movement.
- It will be evident that the details of construction of different portions of the mechanism may be varied without departing from the spirit of the invention. Thus as 40 shown in Fig. 16 the clutch mechanism for rotating the separated stick pieces in twisting the wires may be modified. As shown in said view a cam flange 135 having an inner cam face 136 may be used in the place 45 of the cam ring 82, so also an interior expanding clutch band 137 may be used and operated by levers 138 which are pivoted upon the plate of an inner clutch member or sleeve 139. A clutch drum 140 is used in 50 this instance having an inner band engaging face 141. The said drum is rotated by any suitable friction wheel 142 which bears with a frictional engagement upon the under side of the drum 140. The said friction wheel 55 may be set and clamped upon the actuating shaft 83 so as to bear upon the drum 140 at different distances from the axis thereof, according to the speed with which it is desired to drive the said drum.
- As shown in Fig. 17 also the drum 140 60 of the construction just described with respect to Fig. 16 and having an internal cam 135 operating clutch arms 138, may be driven by a belt 143, instead of by a friction wheel 142. In such an arrangement of the parts 65 the belt would run upon the outer periphery of the drum 140 and around guiding pulleys 144 and thence to a cone or step pulley 145 fixed to the power shaft 23 of the machine. In this instance also the speed at which the 70 drum 140 is driven may be altered by placing the belt upon different portions of the cone or step pulley 145. The pulleys 144 are carried by adjusting bars 146 having a slotted engagement with their securing 75 bolts 147 so that the change of the belt from one portion of the pulley 145 to another portion of greater or less diameter may be compensated for.
- The operation of the several parts of the 80 machine will be readily understood from the above description so that only a brief connected outline of a complete operation need be further given. The sawdust, shavings, chips or other comminuted material is 85 fed to the upper end of the die beneath the plunger 16, a feed hooper 148 being usually provided for directing the material beneath the said plunger, although any other mechanism or means may be used if desired. 90 With the machine in operation, the constantly reciprocating plunger 16 will successively force and compress small quantities of materials into the die one after the other, gradually lengthening the composite 95 bars or sticks and forcing the same past the knives whereby the wire receiving kerfs are formed, and between the wires with their ends twisted together. As the compressed 100 stick lengthens, the wire held portion will be forced into the rotating member or cylinder 52 until a suitable length has entered the same to form a stick or mass of the desired length. In passing through the die 105 sections, the stick of compressed material has been turning the serrated trip wheel 46 and at the proper time one of the pins 110 thereof will draw the trip rod downwardly sufficiently to release the trip piece 92 whereby the rod 90 will be elevated and 110 depressed, whereby the lever 69 will be operated to lower the rotating cylinder for breaking the stick, tightening the clutch bands for rotating the said cylinder and 115 twisting the wires, and causing the cutters to snip the wires midway of their twisted portions. The wires are thus tightly bound 120 about the broken off sticks and the ends of 125

- the wires left in the die are also twisted to receive the next stick. The descending sticks of material drop out of the machine at the bottom of the rotating member in succession.
- 5 The action of the machine is continuous and automatic as long as the main shaft 23 is connected with the source of power by the clutch 26. It will be evident by a glance at Fig. 1 that the parts may be duplicated upon the other side of the machine by connecting duplicate mechanisms with the other end of the shafts 18, 23 and 83 whereby they will be operated, all, within the spirit and scope of the invention. It will be further
- 10 evident that many of the minor details of construction may be changed if desired and mechanical equivalents substituted therefor without departing from the spirit of the invention.
- 15 20 What is claimed is:
1. A material compressing machine comprising a compressing member, a material receiving and shaping member, a material separating and rotating member adapted to be moved longitudinally for separating the material, gearing for actuating the said member, a clutch mechanism connecting said member with said gearing and means for operating the clutch mechanism controlled by the longitudinal movement of the rotating member.
  2. A material compressing machine comprising a compressing member, a receiving and shaping member, a material separating and rotating member adapted to move longitudinally toward and away from the said shaping member, mechanism for turning said rotating member, a clutch mechanism for connecting said mechanism with said rotating member, means operable in conjunction with the movement of the compressing member for moving said rotating member longitudinally and a cam member carried by the rotating member for controlling the clutch mechanism when the rotating member is reciprocated.
  3. A material compressing machine comprising a reciprocating compressing plunger, a material receiving and shaping member, a material separating and rotating member, a clutch mechanism having a member movably engaging the rotating member for turning it and having a gear driven member, gearing for driving said latter member and means operable by the reciprocating movement of the rotating member for connecting the clutch members, whereby said rotating member will be turned about its axis.
  4. In a machine of the class described, the combination with a compressing element and a material receiving and shaping element of a material rotating member adapted to receive and break off suitable

lengths of the compressed material, a clutch sleeve having a splined connection with said rotating member whereby the said rotating member may move longitudinally in said sleeve, an actuating member revoluble upon said sleeve, mechanism for rotating said actuating member, a clutch band adapted to connect the said revoluble member with the said sleeve, a lever for operating the clutch band and a member carried by the said rotating member for engaging and moving the said lever to tighten the clutch band when the rotating member is reciprocated for separating the material.

5. A material compressing machine comprising a compressing element, a material receiving, and shaping element, a clutch member, a material separating and rotating member having a bearing in said clutch member whereby it may be reciprocated therein and rotated thereby, mechanism for rotating the clutch mechanism, a clutch band for causing the clutch mechanism to impart a rotary movement to the rotating member, a lever for operating the clutch band and an annular cam carried by the rotating member and adapted to operate said lever when said member is reciprocated.

6. A machine of the class described having a reciprocating compressing plunger, a material receiving and shaping member, a material breaking and rotating member, means for applying binding wires about the material compressed, a lever for reciprocating the rotating member, an operating arm for moving the same having a cam slot therein, a reciprocating member engaging said slot for actuating the arm, means for moving the said reciprocating member in conjunction with the operation of the compressing plunger, and means for turning the rotating member after the materials have been separated for twisting the binding wires at the ends of the separated portions.

7. A machine of the class described comprising a compressing plunger, a material receiving and shaping die provided with means for applying binding wires to the material compressed, a vertically moving cylinder for receiving the bound materials, a bifurcated lever adapted to raise and lower said cylinder having an operating and locking arm provided with a slotted portion having a cam surface and a locking recess, a reciprocating bar having a projection adapted to engage the said slot for raising and lowering said arm and engaging the recess in the slot for locking the arm when supporting the cylinder in raised position, means for reciprocating said bar, and means for rotating the said cylinder when it is lowered by said lever, to twist the binding wires.

8. A machine of the class described hav-

the twisting member longitudinally, and
ing a reciprocating compressor, a receiving
and forming die mechanism having separ-
able sections with supporting and strength-
ening flanges, one of which is adapted to
rock with respect to the other, a platform
having an opening for receiving said die
sections and having a counter sunk portion
for receiving and bearing against the edges
10 of said strengthening flanges, the counter
sunk opening affording an abutment for the
flanges of the fixed and movable die sec-
tions preventing the separation thereof at
the top, means for controlling their sepa-
15 ration at the bottom, and means for separat-
ing and binding sections of the compressed
material.

9. A machine of the class described hav-
ing a compressing element, a shaping die
20 having means for laying binding wires in
the material compressed, a material sepa-
rating and twisting member, a supporting
and locking lever therefor, adapted to lower
said member for the separating and twist-
25 ing operation, a cutting device having blades
adapted to be thrust between the said die
and the twisting member, a bar for support-
ing the same, adjustable brackets carrying
said bar, a rod connected with the blades
30 and having a cam engaging projection, a
cam plate having an actuating and a re-
turn path for reciprocating said rod, a
switch for directing said cam engaging pro-
jection into said return path and a rod oper-
35 able in conjunction with the compressing
element for operating said supporting and
locking lever and said cam plate when the
wires are to be twisted and cut.

10. A machine of the class described hav-
ing a reciprocating compressor, a material
40 shaping and wire applying die, a twisting
member having a reduced actuating portion,
a clutch engaging the same and having levers
for operating it to turn the twisting member,
45 a cam carried by said twisting member and
adapted to operate the said levers when said
member moves longitudinally, means for
rotating the clutch, and means for moving

means for varying the speed with which the
clutch member is turned.

50

11. A machine of the class described hav-
ing a compressing element, a shaping die, a
material separating and rotating member, a
clutch mechanism having a rotating drum,
levers for connecting said drum with the 55
rotating member, an overhanging flange car-
ried by said rotating member and having
a beveled cam surface for operating said
levers, a shaft for driving the drum, a
friction wheel adapted to be adjusted there-
60 on so as to engage the drum at different dis-
tances from its axis, whereby the speed of
the drum may be changed and mechanism
for driving said shaft.

60

12. A machine of the class described hav-
ing a compressing element, a shaping die, a
material separating and rotating member,
a clutch mechanism having a rotating drum,
a clutch band bearing on the inner surface
of said drum, levers for expanding said band 70
to connect the parts of the clutch, an annular
cam on the rotating member for actuating
said levers and means for driving said
drum.

70

13. A machine of the class described, hav-
ing a compressing element, a shaping die, a
material separating and rotating member, a
clutch member for imparting a rotary move-
ment to said rotating member, said clutch
member having a rotating drum, frictional
means for gripping said drum, levers for
operating said frictional means to impart
the movement of the drum to said rotating
member, a cam for operating said levers, a
cone pulley for furnishing power for said 80
drum, means for rotating said pulley, a
belt for connecting the drum with the said
cone pulley, and adjustable means for keep-
ing said belt taut.

75

In testimony whereof, I have hereunto set 90
my hand, in presence of two witnesses.

IRA D. VINTON.

Witnesses:

LILLIE VOLLMER,
CASSELL SEVERANCE.
